(57) **CLAIM**

The ornamental design for soldering iron tweezers as shown and described.

DESCRIPTION

FIG. 1 is a first perspective view of soldering iron tweezers showing our new design;

FIG. 2 is a second perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a cross-sectional view taken along line 9-9 in FIG. 3 thereof; and,

FIG. 10 is a cross-sectional view taken along line 10-10 in FIG. 3 thereof.

The dash-dash lines depict portions of the soldering iron tweezers in which the design is embodied that are not considered part of the claimed design.

The dot-dash lines show a boundary between the claimed design and unclaimed portions.
